UNITED STATES PATENT OFFICE.

ALBERT C. LIEBENDORFER, OF OTTAWA, ILLINOIS.

DRILLING-MACHINE.

SPECIFICATION forming part of Letters Patent No. 554,940, dated February 18, 1896.

Application filed May 6, 1895. Serial No. 548,320. (No model.)

To all whom it may concern:

Be it known that I, ALBERT C. LIEBENDORFER, a citizen of the United States, residing at Ottawa, in the county of La Salle and State of Illinois, have invented certain new and useful Improvements in Drilling-Machines; and I do hereby declare the following to be a full, clear, and exact description of the invention, such as will enable others skilled in the art to which it appertains to make and use the same.

My invention relates to improvements in drilling-machines, and has more particular relation to machines for drilling wells.

It consists of certain novel constructions, combinations, and arrangements of parts, all of which will be hereinafter more particularly set forth and claimed.

In the accompanying drawings, forming part of this specification, Figure 1 represents a side elevation of a machine embodying my invention. Fig. 2 represents a transverse vertical section through the same. Fig. 3 represents a detail side elevation, partly in section, of the spring-controlling devices. Fig. 4 represents a horizontal section through the same, and Fig. 5 represents a detail section of the cam and mountings for operating the friction-wheel.

A in the drawings represents the truck, of any suitable construction, by which the machine may be moved to the different fields of operation. B is the vertical frame mounted on this truck, C the hollow operating-drill, and D the spring devices for controlling the operation of said drill.

The frame B is mounted on the forward end of the truck, and consists of two vertically and forwardly inclined standards b, attached to the side beams of the truck and held firmly in position by the inclined braces b', also attached to the respective side beams of the machine. A walking-beam b² is pivotally mounted between the standards b and is pivoted at its rear end with a pitman b³ pivotally pendent therefrom. The lower end of said pitman is mounted upon a crank-pin b⁴ of a crank-disk b⁵. This disk is mounted on the inner end of the main operating-shaft b⁶, which is mounted transversely of the truck and under the rear end of the walking-beam by journal-boxes b⁷, attached to the longi-

tudinal beams of the truck. This shaft carries a belt-wheel e, a fly-wheel e', and a friction-wheel e², the latter being composed of a suitable hub or wheel covered about its periphery with leather or some like frictional material.

The spring devices D for controlling the action of the drill consist of an inverted-yoke-shaped frame d, having lateral lugs d', by which it is attached to the transverse beams of the frame of the truck. The vertical arms of this yoke are provided upon their inner faces with vertical guides d², upon which the grooved head d³ is adapted to slide and be guided. This head, as shown in Figs. 3 and 4, is provided upon its upper surface with three circular spring-retaining projections d⁴, the middle one of which is apertured to permit the end of a connecting-rod d⁵ to be passed therethrough and secured by a suitable locking-nut.

The under side of the horizontal portion of the yoke is provided with three tubular pendant projections d⁶ adapted to support the upper ends of the spiral springs d⁷, which are interposed between the head d³ and said horizontal portion of the yoke. The rod d⁵ passes through the middle one of said projections d⁶ and is formed with an eye d⁸ at its upper end. A rod d⁹ having a turnbuckle d¹⁰ connects said rod d⁵ and the pitman b³. An auxiliary shaft F is mounted on the frame A in the rear of the shaft b⁶ and is provided with a reel or drum f, a friction-wheel f' adapted to engage the wheel e² and a cam-disk f², the latter being shown in Fig. 5 with the shaft passing loosely through it to one side of its true center. This cam is provided with an operating-arm f³ which passes through a slot f⁴ cut in the top half of the divided bearing-box f⁵ mounted on the truck-beam and in which the cam is set. The arm f³ is connected to an operating-lever f⁴ pivoted at the front of the machine by a connecting-rod f⁶, said lever being provided with rack and pawl securing devices f⁷ for holding it in the desired adjusted position.

It will be seen from the foregoing that when it is desired to rotate the drum f the lever f⁴ is pushed forward and the shaft F thus forced forward as the cam f² revolves. This action will bring the wheel f' in contact with the

wheel e^2 , and thus the shaft F will be re-
volved and wind the rope f^7 upon the drum,
the said rope passing over a pulley at the top
of the frame B and being provided with a
5 suitable hook f^8 .

The drill C is provided with a suitable hol-
low drill-rod c having two twisting-handles
c' rigid therewith and is screw-threaded at its
10 upper end to work in the temper-screw c^2 , the
latter being attached at its upper end to the
forward end of the walking-beam by a swivel-
joint, and a clamp c^3 being provided at the
15 lower end of the temper-screw to bind the
same in any desired adjusted position on the
rod c. Apertures c^4 are formed in the lower
end of the drill-rod, so that the water, sand,
&c., can pass upward through said rod. When
20 it is desired to rotate the rod c to move it
downward as the drilling progresses, the same
is accomplished by turning the handles c'.

When it is desired to raise or lower the
drill from or into the well to affix a new point
or the like, the temper-screw c^2 is uncoupled
25 from the walking-beam and the hook f^8
hooked in the same. The drum f is then ro-
tated, as before described, and the rope f^7
wound thereon, which will elevate the drill.
If desired, when raising the drill the pitman
30 b³ and rod d⁹ may be uncoupled from the
crank-disk and the rod d⁹ respectively, so that
the spring device D will not operate.

By means of the spring device D, I am en-
abled to produce a sharp quick stroke of the
35 drill, which is more like a rebounding tap
than a steady downstroke as the springs are
compressed as the drill descends, thus slightly
decreasing the force of the stroke and causing
the drill to strike with a quick jerking action,
which I find produces the best results.

40 The drillings pass up through the rod c and
discharge through the handles c'.

Having now described my invention, what
I claim as new, and desire to secure by Letters
Patent, is—

45 1. In a drilling-machine, the combination
of a portable truck carrying a suitable frame,
a walking-beam mounted on said frame, a
drill detachably mounted on the outer end of
said beam, mechanism for reciprocating said
50 beam, spring devices for restraining the
movements of said beam mounted on the
frame and comprising a yoke having inter-
nal vertical guides and pendent cylindrical
spring-supporting projections one of which
55 serves as a guide for a connecting-rod, a head

sliding on said guides, a bar passing through
one of said projections and connecting said
head with the walking-beam, and a plurality
of coil-springs mounted on said projections
and engaging said head, substantially as de- 60
scribed.

2. In a drilling-machine, the combination
of a portable truck carrying a suitable frame,
a walking-beam mounted on said frame, a
drill detachably mounted on the outer end of 65
said beam, mechanism for reciprocating said
beam, spring devices for restraining the
movements of said beam mounted on the
frame and comprising a yoke having inter-
nal vertical guides and pendent cylindrical 70
spring-supporting projections one of which
serves as a guide for a connecting-rod, a head
sliding on said guides, a bar passing through
one of said projections and connecting said
head with the walking-beam, and a plurality 75
of coil-springs mounted on said projections
and engaging said head, a turnbuckle for
increasing or decreasing the length of said
bar, whereby the tension of the springs is de-
creased or increased at will and a tackle and 80
winding-drum for raising the drill independ-
ently of the walking-beam, substantially as
described.

3. In a drilling-machine, the combination
of a portable truck carrying a suitable frame, 85
a walking-beam mounted on said frame, a
drill detachably mounted on the outer end of
said beam, mechanism for reciprocating said
beam, spring devices for restraining the
movements of said beam mounted on the 90
frame and comprising a yoke having inter-
nal vertical guides and pendent cylindrical
spring-supporting projections one of which
serves as a guide for a connecting-rod, a head
sliding on said guides, a bar passing through 95
one of said projections and connecting said
head with the walking-beam, and a plurality
of coil-springs mounted on said projections
and engaging said head, a winding-drum and
tackle and means for moving said drum into 100
or out of engagement with the moving parts
of the machine at will, substantially as de-
scribed.

In testimony whereof I hereunto affix my
signature in presence of two witnesses.

ALBERT C. LIEBENDORFER.
